UNITED STATES PATENT OFFICE

WILLIAM F. CONRAN, OF BROOKLYN, NEW YORK

STANDPIPE SYSTEM

Application filed May 8, 1928. Serial No. 276,061.

This invention relates to fire extinguishing apparatus for buildings or other structures or places in which a standpipe having a plurality of nozzles at different levels is employed. Apparatus of this general character is disclosed in my Patents Nos. 816,152, dated March 27, 1906, 1,156,978, dated Oct. 19, 1915, and 1,253,005, dated Jan. 8, 1918.

A requisite of apparatus of this character is to secure the maximum coverage by the discharge from the nozzles, both by lateral and vertical movement thereof, and heretofore this coverage has been secured by mounting the nozzles rigidly with respect to the standpipe and turning and lifting the latter as a whole in order to secure the desired distribution of the extinguishing fluid. Rotation of the standpipe is relatively easy to accomplish, but vertical movement, due to the weight of the structure, involves the use of power mechanism for this purpose.

According to the present invention, a standpipe is employed to which other nozzles are movably secured in a manner permitting vertical movement thereof without necessitating vertical movement of the standpipe. This not only eliminates the standpipe lifting mechanism but also permits independent vertical movement of the nozzles. The invention further provides power operated means for moving each nozzle, which means may be controlled from a central operating station at or adjacent to which is located the means for rotating the standpipe. Thus the desired distribution from the standpipe nozzles is secured by rotation of the standpipe and by individual movement of the nozzles, giving a degree of flexibility in the operation of the apparatus not heretofore obtainable. In addition, the invention provides means whereby the range of vertical movement of the nozzles and the position of the range may be adjusted to suit individual installations.

The standpipe is built up of a number of pipe sections connected by fittings carrying the nozzles and other parts of the apparatus, and a further feature of the invention consists in a novel form of screwed joint between the pipe sections and the fittings.

Screwed joints are for various reasons to be preferred to flanged and bolted joints in structures of this character, but the ordinary form of screwed joint is likely to become unscrewed by the torsional stresses set up by repeated turning of the standpipe. In accordance with the present invention the fittings and pipe sections are bonded together after assembly in a manner which makes the standpipe as a whole a substantially unitary structure and eliminates the above objection to the screwed joint.

The more specific features and objects of the invention will appear more fully from the following description of the several embodiments of the invention illustrated in the accompanying drawings, in which:

Fig. 1 is an elevation of a standpipe constructed in accordance with the invention, certain sections being omitted; Fig. 2 is an elevation, partly in section and on an enlarged scale, of one of the nozzle fittings shown in Fig. 1; Figs. 3 and 4 are views taken, respectively, on the lines 3-3 and 4-4 of Fig. 2; Fig. 5 is a view similar to Fig. 2 of another form of nozzle fitting; Fig. 6 is a section taken on the line 6-6 of Fig. 5; Fig. 7 is a view similar to Fig. 2 of a third form of nozzle fitting; Fig. 8 is a plan view of Fig. 7; Fig. 9 is a section taken on the line 9-9 of Fig. 7; and Fig. 10 is a section taken on the line 10-10 of Fig. 1.

Referring now to Fig. 1, the standpipe, indicated generally at A, comprises a number of pipe sections 1, joined by the nozzle fittings B, C and D and the operating station fitting E. The bottom pipe section 1 is closed by a cap 2 carrying the supporting pin 3 which is rotatably mounted in a suitably recessed bearing pedestal 4. In the form illustrated, the standpipe extends upwardly through the floors 5 of a building and receives lateral support from the bearing sleeves 6, but it is to be understood that the invention may be equally well applied to standpipes located exteriorly of a building and supported in a different manner. A T-fitting 7, provided with the usual standard Siamese connection 8, forms the inlet to the standpipe, and a lever 9, preferably adjacent to

the operating station, provides means for manually turning the standpipe. In this operation the standpipe is oscillated about its axis through suitable angular distances to secure the desired lateral or radial coverage at the several floors or levels.

In Fig. 2 is shown the form of nozzle fitting and actuating mechanism indicated at B in Fig. 1. This comprises the cast fitting 10, joining the pipe sections 1 in a manner to be described in detail later, and provided with a branch 11 bifurcated at its outer end (in the manner shown more clearly in Fig. 8) to provide a pivoted connection 12 for the nozzle 13, which may be attached through the medium of any suitable form of fluid-tight rotatable joint. The branch 11 has an angularly disposed valve seat 14 formed therein adapted to be engaged by a disc valve 15 to close communication between the standpipe and the nozzle. Valve 15 is mounted on a stem 16 passing through a stuffing-box 17 in the bottom of a cylinder 18 which forms a cover plate for the extension 19 forming part of branch 11. A piston 20 attached to the upper end of stem 16 and mounted in cylinder 18 controls the position of valve 15.

A spring 21 acting on the piston normally holds valve 15 closed, and the latter is opened by the admission of pressure fluid below the piston through the control pipe 22. Pipe 22 passes through the wall of the fitting 10 and is carried within the standpipe to the operating station in the manner disclosed in Patent 1,253,005 granted to me January 8, 1920.

A casing 23, mounted on arm 24, supports a rotatable shaft 25 which extends at one end through the wall of the casing and carries within the latter an impeller 26. The extended end of shaft 25 has secured thereto the block 27 provided with an undercut slot receiving the head of a clamping bolt 28 which passes through the eye of a threaded rod 29. A bushing 30, of greater thickness than the eye of the rod 29, permits the bolt 28 to be clamped by means of a nut 31 at any desired point in the slotted block without binding the rod 29, which is freely rotatable on the bushing. The threaded end of rod 29 is connected by means of the turnbuckle 32 to a forked rod 33 the arms of which are pivotally connected to the nozzle 13. A pipe 34 connects the branch 11 from a point beyond valve 15 to the inlet side of the impeller 26, which discharges to the flexible pipe 35. Pipe 35 is preferably attached to the nozzle 13.

The operation of the nozzle is largely obvious. Admission of pressure fluid through pipe 22, controlled from the operating station, opens valve 15 and permits flow from the standpipe to the nozzle and also through pipe 34 to impeller 26. Rotation of the im-

peller shaft, and with it block 27, imparts an oscillatory motion to the nozzle through rods 29 and 33.

The range of oscillation of the nozzle is determined by the position in which bolt 28 is clamped in block 27, and it will be readily apparent that by means of this adjustment the range of play of the stream from the nozzle can be varied to suit the requirements of different installations. Further, by means of the turn-buckle 32, the position of the entire range of oscillation of the nozzle may be varied so that the discharge therefrom may be directed over areas at different distances from the standpipe.

Fig. 5 illustrates another form of oscillating nozzle driven by fluid under pressure from the standpipe, which differs from the form heretofore described in the type of actuating mechanism employed. In this form (indicated at C in Fig. 1), the fitting 10^a comprises a branch 11^a to which the nozzle 13^a is pivotally mounted as heretofore described. An arm 24^a terminates in a cylinder 36 in which is located the piston 37. The piston rod 38 passes through a suitable stuffing-box in the end of cylinder 36 and is secured at its outer end in a cross-head block 39 held between the guides 40. The cross-head is connected by means of the forked connecting rod 41 to the nozzle 13^a. Operating fluid taken from the branch 11^a at a point beyond the control valve 15^a through pipe 34^a enters the valve chest 42 and is admitted to cylinder 36 by the D slide valve 43 through inlet passages 44. The outlet port 45 discharges to the flexible pipe 35^a attached to nozzle 13^a. The valve 43 is actuated from the cross-head 39, which carries a pin 46 engaging the bifurcated end 105 of one arm of the forked lever 47 pivoted to an extension on the guide 40. A bell-crank 48, also pivoted on this extension but offset from the plane of lever 47 (as will be seen in Fig. 6), has a short bifurcated arm terminating at a point between two of the arms 110 of lever 47 and a longer arm to which is attached the weight 49.

A pin 50, set in the valve rod 51, engages the bifurcated arm of crank 48 and is adapted to be moved by either of the arms of lever 47 between which it projects. The operation of the mechanism, when pressure fluid is admitted thereto, is the same as that of the ordinary reciprocating pump, except for the action of the weighted crank 48. As the operating fluid is ordinarily water, which is non-expansive, provision must be made for shifting the valve 43 after the point of cut-off on a given stroke has been reached, and this is accomplished by the weighted crank. It will be obvious from Fig. 5 that as the valve is shifted from the operation shown in the figure by one arm of lever 47, the weight 49 will be moved past an upper 125

dead center, after which point gravity will act to carry the weight downward and through the medium of the crank 48 and pin 50 move the valve to the end of its stroke independently of the action of lever 47. The return stroke is accomplished by action similar to that just described.

In the form of nozzle mechanism shown in Fig. 7 the elevation or depression of the nozzle is under the control of the operator and the nozzle may either be held stationary or reciprocated by proper manipulation of the controls. The fitting 10^b is generally similar in form to those previously described, having a branch 11^b controlled by the valve 15^b and carrying at the end of the branch the pivoted nozzle 13^b. The arm 24^b carries a cylinder 36^b in which the piston 37^b is located. Piston rod 38^b, extending through the usual stuffing-box, is connected to the nozzle by rods 29^b and 33^b and the turn-buckle 32^b, so that adjustment in the position of the nozzle may be effected as described in connection with the form of mechanism shown in Fig. 2.

Rod 38^b carries a laterally extending arm 52 adapted to engage an adjustable stop 53 threaded through a supporting arm 54 and locked in position by the nut 55. A spring 56 serves to force the piston 37^b to one end of the cylinder, while pressure fluid admitted to the opposite side of the piston through the control pipe acts to move the piston against the action of the spring to the other end of the cylinder. Obviously, the adjustable stop 53 serves to limit the range of motion of the nozzle by limiting the stroke of the piston.

In all of the forms described, control of the flow from the standpipe to the nozzles is effected by manipulation of the three-way valves 58 at the operating station which admit fluid from the standpipe to the pipes 22, 22^a and 22^b in the manner described in my previously mentioned Patent No. 1,253,005.

Admission of fluid to pipes 22 and 22^a also sets the nozzle reciprocating mechanism for the respective nozzles in motion, but admission of fluid to pipe 22^b only admits fluid to the nozzle. Movement of this nozzle is controlled by manipulation of the three-way valve 59, which admits fluid from the standpipe to the control pipe 57.

In order to prevent the possibility of failure of the standpipe apparatus through loosening of screw joints between its parts resulting from repeated turning of the standpipe in opposite directions, I provide that these joints shall be rendered integral wherever they occur, whereby it results that the structure is substantially unitary once it has been assembled. Preferably the nozzle fittings 10, 10^a, 10^b and also the T-connection 7 are provided with internally threaded shoulders 60 (Fig. 2) into which the pipe sections 1 are screwed. These shoulders are

short of the counterbored end sections 61, which with the pipe sections 1 form annular spaces 62. These spaces, after assembly of the standpipe, are filled with any suitable bonding compound. For example, a mixture of iron filings and sal ammoniac may be employed to produce a so-called "rust" joint which bonds the joined elements into a substantially integral whole, so much so that before the standpipe could be taken apart it would be necessary to break the fittings.

As a further means of resisting the torsional stress at the joints, the set screws 63 may be employed. These screws are effectively prevented from becoming loose by the action of the bonding compound surrounding them between the fitting and the pipe section.

It is to be understood that the forms of apparatus hereinbefore described are merely illustrative and may be modified both in form and arrangement without departing from the invention. For example, the number of nozzles employed may be varied in accordance with the particular requirements of the installation, and any one particular type or combination of types of nozzle operating mechanism may be utilized. Further, it is not intended that the invention is to be limited to the specific details of construction described but is to include all such equivalents and variations as may fall within the scope of the appended claims.

The fluid employed is customarily a liquid, typically water under pressure obtained in any suitable way, but vapors or gases, or mixtures, are not excluded.

The invention is especially adapted for installation inside buildings or other structures, but as indicated in my prior patents such standpipes may be disposed outside the structure in close proximity thereto, and indeed the apparatus may be installed in any place where it may be employed to advantage.

I claim:

1. A rotary standpipe comprising a pivoted discharge nozzle and a control station remote from the nozzle, a connection adapted to supply fluid under pressure to the standpipe, means at the control station for rotating the standpipe to vary the lateral direction of the discharge from the nozzle, means actuated by fluid under pressure from the standpipe for moving the nozzle about its pivot to vary the vertical direction of the discharge therefrom, and means at the control station for controlling the last-named means.

2. A rotary standpipe comprising a plurality of pivoted discharge nozzles, a central control station, a connection adapted to supply fluid under pressure to the standpipe, means at said station for rotating the standpipe to vary the lateral direction of the discharge from the nozzles, fluid actuated means for separately moving each of said nozzles

about its pivot to vary the vertical direction of the discharge therefrom, and means located at the control station for separately controlling each of said second named means.

- 5 3. A rotary standpipe comprising a plurality of pivoted discharge nozzles, a connection adapted to supply fluid under pressure to the standpipe, means for rotating the standpipe to vary the lateral direction of the 10 discharge from the nozzles, fluid pressure actuated means associated with each nozzle for moving it about its pivot to vary the vertical direction of the discharge therefrom, conduits connecting each of said last-named 15 means with the interior of the standpipe, and means located adjacent to said first-named means for controlling flow from the standpipe through each of said conduits.

4. In apparatus of the class described, the 20 combination with a standpipe to which fluid under pressure is supplied and which has an operating station, of a plurality of pivoted nozzles for discharging fluid from the standpipe, separate means associated with each of 25 said nozzles for changing its angular position, and means located at the operating station for separately controlling each of said first-named means.

5. In apparatus of the class described, the 30 combination with a standpipe to which fluid under pressure is supplied and which has an operating station, of a plurality of pivoted nozzles for discharging fluid from the standpipe, separate fluid pressure actuated means for changing the angular position of each of said nozzles, conduits connecting the interior of the standpipe with each of said means, and valves located at the operating station for controlling the admission of fluid under pressure to each of said conduits.

6. In apparatus of the class described, the combination with a fire-protection standpipe installed in a building, of a plurality of pivoted nozzles at different elevations on the standpipe, said nozzles being movable between a depressed and an elevated position, resilient means for moving each of the nozzles in one direction, fluid pressure actuated means for moving each of the nozzles in the other direction, connections for admitting fluid under pressure to said last-named means, and means for controlling said connections individually.

7. In apparatus of the class described, the 55 combination with a fire protection standpipe installed in a building, of a plurality of pivoted nozzles at different elevations on the standpipe, said nozzles being movable between a depressed and an elevated position, resilient means for moving each of the nozzles to their depressed positions, fluid pressure actuated means for moving each of the nozzles to their elevated positions, connections for admitting fluid under pressure from the 60 standpipe to said last-named means, and

means for controlling said connections individually.

8. In apparatus of the class described, the combination with a standpipe to which fluid under pressure is supplied and which has an operating station, of an angularly movable nozzle for discharging fluid from the standpipe, means responsive to the admission of fluid from the standpipe for changing the angular position of the nozzle, a fluid pressure actuated valve for admitting fluid to the nozzle, and means located at the operating station for separately controlling said valve and admitting fluid from the standpipe to said first-named means.

9. In apparatus of the class described, the combination with a standpipe to which fluid under pressure is supplied, of a pivoted nozzle movable between a depressed and an elevated position, a resilient means for moving the nozzle to its depressed position, fluid pressure actuated means for moving the nozzle to its elevated position, a conduit connecting said fluid pressure actuated means with the interior of the standpipe, a fluid pressure actuated valve for admitting fluid to the nozzle, a conduit connecting said valve with the interior of the standpipe, and valves located at the operating station for controlling both of said conduits.

10. In apparatus of the class described, a standpipe fitting comprising a discharge branch, a nozzle pivoted to said branch, a valve controlling said branch, a fluid pressure actuated piston for opening said valve, a cylinder mounted on an arm of said fitting, a piston in said cylinder, a positive mechanical connection between the last-named piston and the nozzle, a spring located in said cylinder and acting on one side of said piston, and a fluid pressure inlet in said cylinder on the other side of said piston.

11. In a fire-protection standpipe system, the combination with a standpipe, of a pivoted nozzle for discharging fluid from the standpipe, a fluid-actuated device for changing the angular position of the nozzle, and a connection leading from said fluid-actuated device to a remote control station and there provided with a control enabling said device to be operated or not when fluid is being discharged through the nozzle.

12. In a fire-protection standpipe system, the combination with a standpipe, of a branch carrying an angularly movable nozzle, a fluid-actuated valve for opening and closing said branch, a fluid-actuated device for changing the angular position of the nozzle, separate fluid connections extending from said valve and said device to a remote control station, and means at said station for separately controlling said connections.

13. In a fire-protection system, the combination with a standpipe, of a pivoted nozzle for discharging fluid from the standpipe, a

valve adjacent said nozzle controlling discharge therefrom, means at a remote control station for controlling said valve, a fluid-actuated device for moving the nozzle on its pivot, 5 and a fluid connection extending from said device to said control station and there provided with means for independently controlling said device.

14. A fire-protection standpipe system installed in a building and having a plurality of branches at different floors, angularly movable nozzles carried by said branches, fluid-actuated devices associated with the several nozzles for elevating and depressing the nozzles, fluid connections extending to a remote control station and there provided with means for separately controlling said devices, and means for independently varying the range of the angular movement of the several nozzles. 20

15. A fire-protection standpipe system installed in a building and having a plurality of branches at different floors, angularly movable nozzles carried by said branches, fluid-actuated devices associated with the several nozzles for elevating and depressing the nozzles, fluid connections extending to a remote control station and there provided with means for separately controlling said devices, and means for independently varying the position of the range of angular movement of the several nozzles. 30

16. A fire-protection standpipe system installed in a building and having a plurality of branches at different floors, angularly movable nozzles carried by said branches, fluid-actuated devices associated with the several nozzles and adapted to move the same, and fluid control means for separately controlling said devices from a remote control station. 35

17. A fire-protection standpipe system installed in a building and having a plurality of branches at different floors, angularly movable nozzles carried by said branches, fluid-actuated devices associated with the several nozzles to move the same in vertical planes, fluid-actuated valves for opening and closing said branches, and fluid control means for controlling any of said valves and devices 50 from a central station.

18. In a building, a rotary fire-protection standpipe having a plurality of vertically movable nozzles at different levels, means located at a control station for turning the standpipe to change the lateral direction of the streams that can be discharged from the nozzles, a device associated with each nozzle for moving it vertically relatively to the standpipe, a valve between each nozzle and the standpipe, and means for controlling the valves and devices of any one or more of the nozzles from the control station. 55

19. A rotary standpipe comprising a plurality of pivoted discharge nozzles, a connection adapted to supply fluid under pressure to

the standpipe, means for rotating the standpipe to vary the lateral direction of the discharge from the nozzles, fluid-pressure-actuated means associated with each nozzle for reciprocating it about its pivot, and means for selectively controlling the admission of fluid to each nozzle and its associated reciprocating means. 70

20. A rotary standpipe comprising a plurality of pivoted discharge nozzles, a connection adapted to supply fluid under pressure to the standpipe, means for rotating the standpipe to vary the lateral direction of the discharge from the nozzles, a fluid-pressure-actuated motor associated with each nozzle for reciprocating it about its pivot, valves for admitting fluid from the standpipe to each nozzle and its motor, fluid-pressure-actuated means for opening each valve, conduits connecting each of said last named means with the interior of the standpipe, and valves in each of said conduits for controlling the same. 75

21. In apparatus of the class described, the combination with a standpipe to which fluid under pressure is supplied and which has an operating station, of a plurality of pivoted nozzles located at different elevations, a plurality of fluid-pressure-actuated motors each adapted to reciprocate a nozzle about its pivot, a plurality of fluid-pressure-actuated valves each controlling the admission of pressure fluid to a nozzle and its motor, and a plurality of means each controlled from said operating station for admitting operating fluid to said valves. 80

22. In apparatus of the class described, a standpipe fitting having a discharge branch, a nozzle pivoted to said branch, a fluid-pressure-actuated motor mounted on said fitting for imparting reciprocatory motion to the nozzle, a fluid-pressure-actuated valve in said branch for controlling fluid flow to the nozzle, a conduit connecting said motor with said branch at a point between the valve and the nozzle, and means for admitting pressure fluid to actuate the valve. 90

23. In apparatus of the class described, a standpipe fitting having a discharge branch, a nozzle pivoted to said branch, a rotary fluid-pressure-actuated motor mounted on said fitting, mechanism connecting the motor with the nozzle comprising means whereby rotation of the motor imparts reciprocatory motion to the nozzle, a fluid-pressure-actuated valve in said branch for controlling fluid flow to the nozzle, a conduit connecting said motor with said branch at a point between the valve and the nozzle, and means for admitting pressure fluid to actuate the valve. 100

24. A fire-protection standpipe system having a plurality of branches provided with pivoted nozzles at different levels, fluid-actuated motors associated with the several branches and capable of reciprocating the 105 110 115 120 125 130

nozzles, valves controlling admission of fluid to the several branches, and a central control station having means for operating any of said valves independently of others and for similarly controlling said motors.

25. A fire-protection standpipe system having a plurality of branches provided with pivoted nozzles at different elevations, means operable at a central control station for 10 swinging the nozzles laterally, fluid-actuated motors associated with the several branches and capable of reciprocating the nozzles in vertical planes, valves controlling the admission of fluid to the several branches, 15 and means at the central control station for operating any of said valves independently of others and for similarly controlling said motors.
